EWING, OF GALLATIN, TENNESSEE.

SIGNAL SYSTEM.

No. 800,547.

Specification of Letters Patent.

Patented Sept. 26, 1905.

Application filed January 16, 1905. Serial No. 241,261.

To all whom it may concern:

Be it known that I, WILLIAM B. BRUCE, a citizen of the United States, and a resident of Gallatin, in the county of Sumner and State 5 of Tennessee, have invented a new and Improved Signal System, of which the following is a full, clear, and exact description.

Many serious collisions have occurred on railroads because no means was provided for 10 signaling trains between telegraph-stations. Such signals have not been provided because no practical one that was absolutely sure to operate when set has been placed upon the market.

15 The main object of my invention is to provide such a signal system—one that will be absolutely certain to operate and one which will be simple and practical in every respect and inexpensive to manufacture and 20 maintain.

Reference is to be had to the accompanying drawings, forming a part of this specification, in which similar characters of reference indicate corresponding parts in all the 25 figures.

Figure 1 is a perspective view showing one form of my invention in position for use. Fig. 2 is a vertical sectional view of the operating means upon an enlarged scale. Fig. 3 30 is a sectional view on the line 3 3 of Fig. 2 on an enlarged scale, and Fig. 4 is a diagrammatic view showing electrical connections for operating the device.

My invention contemplates the placing of 35 one of more signals between every two stations and providing electrical connections between the signals and the stations in both directions, so that by the manipulation of a button or switch at the station all of the signals between that station and the next one 40 in one direction can be set, or those between the same station and the next one in the other direction, if desired.

The signal device which I have illustrated 45 comprises a frame 11, adapted to be set up at any point along the railroad and provided with an upward extension 12 for concealing a signal 13 when the latter is not set to stop a train. It is also provided with a box 14 for 50 receiving the operating parts of the device.

The signal is pivoted upon a rod 15 by means of an arm 16, and the lower end of this arm, which projects below the pivotal point, is

connected by means of a link 17 with a lever 18. This lever is pivoted upon the frame at 55 the point 19 and is provided with a short arm 20, which when the signal is concealed is adapted to assume the position shown in dotted lines in Fig. 2. In this position a stop 21 is preferably inserted in a pair of perforations 22 in the box. This stop is preferably made of a fragile material—as, for example, glass, clay, paper, or the like—and is also preferably made in the form of a receptacle for receiving an explosive 23 and is provided with a cap 24. To this receptacle are connected terminals 25 for exploding the explosive by an electric circuit 26.

It will be readily understood that upon the closing of the circuit from a station or from 70 any other point the explosive will be exploded, the fragile stop destroyed, and the short end 20 of the lever (which is illustrated in the form of a weight) will drop, carrying 75 upwardly the other end and the link 17 and forcing the signal out of vertical position, so that it will drop into horizontal position, as shown in Fig. 2. After the signal has been operated it will be necessary for a new receptacle with explosive to be supplied and the 80 signal placed in normal condition.

The electric circuit is represented in diagrammatic form in Fig. 4 and comprises a generator 27 and switch 28, as well as the terminals 25 mentioned above. In addition to 85 these a shunt 26^a may be taken from the main line and caused to pass through a light 29 in the signal itself. The ends of the circuit may be taken to the ground or a complete metallic circuit may of course be employed, if desired. It will be apparent that upon the closing of the switch 28 a current will be sent through the light 29 and the explosive 23 will be exploded to set the signal 13. This may be accomplished upon all the 95 signals between two stations, if desired, and the connections at the various stations may be made in any way, so as to provide for setting one or more of the signals, as desired. The light described above may be, if desired, 100 provided by a storage battery for each signal sufficient to produce the necessary light in the signal.

It will of course be understood that the details illustrated in the drawings are furnished 105 for the purpose of showing the principle of

my invention and that it is not limited thereto, being capable of variations within wide limits, as represented in the claims.

Having thus described my invention, I claim as new and desire to secure by Letters Patent—

- 5 1. A signal system, comprising a movable signal, a fragile stop for holding the signal out of operative position, and means for causing the signal to be moved into a position indicating danger when said stop is broken.
- 10 2. A signal system, comprising a signal, a fragile stop therefor, means for displaying the signal when the stop is broken, and means for breaking the stop from a distance.
- 15 3. A signal system, comprising a plurality of signals between stations, electric connections from each station to all the signals between it and the next station on each side, a fragile stop for each signal, means for displaying each signal when its stop is broken, and means at each station for breaking said stops.
- 20 4. In a semaphore, the combination of a movable signal, a lever for moving it, a fragile stop for holding the lever out of operative position, and means for fracturing the stop.
- 25 5. In a semaphore, the combination of a movable signal, a lever for moving it, a fragile receptacle for holding the lever out of operative position, and electric means for fracturing the receptacle to allow the lever to operate the signal.
- 30 6. In a semaphore, the combination of a signal, means for moving it, a fragile receptacle for holding said means out of operative position, an explosive within said receptacle, and means for exploding the explosive and
- 35 40 7. The combination of a signal, means for normally holding said signal in a vertical position, said means comprising a lever and a fragile stop therefor, and means for destroying said stop and permitting the signal to be displayed, said means comprising an electric circuit.
- 45 8. The combination with a box having a

projection; a signal pivoted to the box and normally in position behind said projection, 50 a link connected with said signal, a lever connected with the link, means for normally holding the lever in such a position as to keep the signal behind said projection, and means for removing said first-mentioned means so 55 as to allow the lever to turn about its fulcrum and cause the signal to be displayed.

9. The combination with a box having a projection, a signal pivoted to the box and normally in position behind said projection, 60 a link connected with said signal, a lever connected with the link, means for normally holding the lever in such a position as to keep the signal behind said projection, and means for removing said first-mentioned means so 65 as to allow the lever to turn about its fulcrum and cause the signal to be displayed; said first-named means comprising a fragile receptacle, an explosive in said receptacle, an electric circuit connected with said explosive 70 and normally open, and a switch in said electric circuit.

10. The combination with a box having a projection, a signal pivoted to the box and normally in position behind said projection, 75 a link connected with said signal, a lever connected with the link, means for normally holding the lever in such a position as to keep the signal behind said projection, and means for removing said first-mentioned means so 80 as to allow the lever to turn about its fulcrum and cause the signal to be displayed; said first-named means comprising a fragile receptacle, an explosive in said receptacle, an electric circuit connected with said explosive 85 and normally open, a switch in said electric circuit, a shunt connected with said circuit, and an electric light on said signal and connected with said shunt.

In testimony whereof I have signed my 90 name to this specification in the presence of two subscribing witnesses.

WILLIAM B. BRUCE.
